UNITED STATES PATENT OFFICE

LOUIS F. MAISTO, OF BROOKLYN, NEW YORK, ASSIGNOR OF ONE-HALF TO COLOMBO
MAISTO, OF BROOKLYN, NEW YORK

DESIGN FOR A COMBINED CIGAR LIGHTER AND WATCH

Application filed April 29, 1931. Serial No. 39,650. Term of patent 3½ years.

To all whom it may concern:

Be it known that I, LOUIS F. MAISTO, a citizen of the United States, residing at Brooklyn, in the county of Kings and State of New York, have invented a new, original, and ornamental Design for a Combined Cigar Lighter and Watch, of which the following is a specification, reference being had to the accompanying drawing, forming part thereof.

The figure is a perspective view of the combined cigar lighter and watch. The opposite side thereof has substantially the same appearance as the side shown in the figure.

I claim:

The ornamental design for a combined cigar lighter and watch substantially as shown and described.
